UNITED STATES PATENT OFFICE.

WILLIAM E. HORNE, OF DECATUR, ILLINOIS, ASSIGNOR TO REMSEN SCHENCK, OF NEW YORK, N. Y.

DEVICE FOR RAISING OR LOWERING WINDOWS.

SPECIFICATION forming part of Letters Patent No. 377,457, dated February 7, 1888.

Application filed August 13, 1885. Serial No. 174,343. (No model.)

To all whom it may concern:

Be it known that I, WILLIAM E. HORNE, a citizen of the United States, residing at Decatur, in the county of Macon and State of Illinois, have invented a new and useful Device 5 for Raising or Lowering Window-Sashes, of which the following is a specification.

My invention relates to devices for the easy raising or lowering of window-sashes, more particularly the upper one; and my object is to provide the sash with apparatus for this purpose, which may be conveniently manipulated, and at the same time shall not interfere at all with the movement of the sash. I attain 15 these objects by the mechanisms illustrated in the accompanying drawings, in which—

Figure 1 is a front elevation of the invention as applied to a window; and Fig. 2, a side elevation of the same, partly in section, in the 20 line $x y$, Fig. 1.

Similar letters of reference indicate corresponding parts.

A is a bracket secured to the side and top rails on the inner edges in the corner of the sash 25 and flush with or below the face thereof.

B is a rod extending along the inner edge of the sash and attached by a rivet, C, to the bracket A, and allowing the rod B to swing in a plane with the glass F, as shown by the 30 dotted lines D, giving room for a hand to grasp the rod B and operate it without inconvenience from the sash.

A different bracket and attachment, but for the same purpose and on the same principle, 35 is shown in the drawings, and for convenience in illustrating is applied to the lower sash.

E are the side and top bars of the sash.

A' is a bracket attached to the inner edge of the sash in the manner already described. The bracket A' has a hollow or cupped receptacle, 40 having a hole, as shown, through which the rod B passes. The rod B has a loop or solid head, C', by which it is retained in the bracket and allowed to move in a plane with the glass, as shown by the dotted lines D in Fig. 1. 45

The object attained by the illustrated device may also be attained by passing a nail, screw, or screw-eye through a hole in the rod B, the hole in the rod being large enough to allow the rod to be swung from the sash and operated as 50 heretofore described; but I have chosen the styles shown as best illustrating the invention.

I am aware that it is not altogether new to raise a window by means of a rod attached to the sash; but there is no device known to me 55 wherein the construction and arrangement of the parts are such as to admit of the lower sash being raised to its full height, or the upper one lowered to the bottom, as in my invention.

I therefore claim as my invention— 60

In a device for raising and lowering window-sashes, the combination of the sash and a rod pivotally connected with the top rail thereof and flush with or below its face, whereby the rod may be swung sidewise to allow the hand 65 to grasp it, and the sash may be raised or lowered its entire length without interfering with the other one, substantially as described.

WILLIAM E. HORNE.
